UNITED STATES PATENT OFFICE

STUART DEAN, OF INDIANAPOLIS, INDIANA

COMBINATION DRIVE AND OIL PUMP

Continuation in part of application Serial No. 219,868, filed September 16, 1927. This application filed July 18, 1928. Serial No. 293,742.

This invention relates to a lubricating system for pumps and the like.

The chief object of the invention is to provide means for lubricating an overhead shaft and piston rods with a minimum amount of power and number of parts.

The chief feature of the invention consists in a gear running in an oil reservoir and meshing with another gear in superposed relation and discharging the lubricant into an overhead distributing passageway, the discharge being facilitated by the addition of lubricant confining and conveying plate or wall means. This invention is an improvement upon and a continuation in part of the invention shown and described in the pending application, Serial No. 219,868, filed Sept. 16, 1927, entitled "Pump Mechanism".

The full nature of the invention will be more fully understood from the accompanying drawings and the following descriptions and claims:

In the drawings Fig. 1 is a vertical sectional view of a pump mechanism embodying the invention, the same being taken on line 1—1 of Fig. 2 in the direction of the arrows. Fig. 2 is a vertical sectional view taken at right angles to Fig. 1 and on line 2—2 in the direction of the arrows. Fig. 3 is a top plan view of the combination cover plate and oil-distributing passageway.

In the drawings 10 indicates a housing or oil receptacle forming a chamber and said housing is adapted to contain lubricant, at least to a sufficient level so that the driving gear 11 mounted on the crank shaft 12, rotatably supported at bearings 13 provided in said housing, will run in the lubricant. Preferably the oil level is coincident with the crank shaft level. The crank shaft bearings might be otherwise supported within the reservoir.

Supported in spaced relation by standards 14 is a cylinder construction herein having base 15 which slidably supports piston rods 16, which mount pistons 17 in the cylinders 18 of the pump construction including the head portion 19. The unitary piston rod of one or more lengths may or may not be provided with a petticoat construction 20, de-

tails of which are fully explained in the before-mentioned application, and said piston rods extend downwardly thru the housing, thru the space between the cylinders and the housing and extend into the housing thru 55 suitable bearings. The piston rods are pivotally connected at 21 to a link 22 and the opposite end of each link 22 is pivotally supported at 23 by a triangular actuator 24 and at the opposite vertices thereof. The other 60 vertex end, and preferably the uppermost vertex, is mounted upon the crank shaft 12 at the crank portion 25 thereof. The triangular actuator is confined to an oscillatory movement by the links 26 pivotally supported at 65 27 intermediate the two link pivots 23 and in alignment with the crank shaft pivotal support of the triangular actuator and links 26 are pivotally supported at 127 in the reservoir.

Rotation of the crank shaft by gear 11 causes the oscillator 24 to oscillate which causes alternate reciprocation of the parallel piston rods of a duplex pump.

A suitable cover 30 includes the bearings 75 31 for the piston rods and also provides transverse bearings 32 for the shaft 33 superposed relative to the crank shaft 12. Shaft 33 has a projecting end which mounts a wheel 34 for belt driving. The shaft may be otherwise driven if desired. Lateral displacement of the shaft is prevented by the collars 35 which are positioned adjacent the bushings 36 mounted in the bearings 32. The shaft 33 supports a driving pinion 37 which meshes 80 with the driving gear 11. The cover plate 30 includes the anchorages 38 for securing the same to the housing or oil chamber. The wall 39 defines a passageway for distributing oil discharged on to the cover plate thru the 85 opening 40 defined by the wall 41. The cover plate has a plurality of piston rod bearings 31 lubricated by the oil in the passageways and also gravity-fed openings 42. Said openings 90 register with openings 43 formed in bushings 36 or a similar construction so that the power shaft bearings are thus lubricated by oil which works its way outwardly along the shaft thru the bushings 36 and discharges into a peripherally enveloping collecting 95 100

trough 44 formed in or upon the housing, and said trough communicates with the passageway 45 that discharges inwardly into the reservoir or chamber, and the discharge end of said passageway 45 is so arranged that it will discharge into the passageway 46 formed in the crank shaft bearings 13 so that the lubricant which works its way outwardly along the crank shaft and the bearings will discharge into the chamber thru the relief passageway 47.

Gear 11 which meshes with pinion 37 carries a lubricant from the bottom of the reservoir or chamber to near the top thereof. Meshing engagement between the gears transfers the oil from the gear to the pinion and the pinion throws the oil into the opening 40, defined by walls 41 and into the passageway defined by the wall 39. To secure positive discharge of the lubricant, plate or wall, means are provided for overlapping the gears at the meshing engagement and said wall or plate means extends toward the opening 40. Herein, the aforesaid consists of a pair of plates 50 having the hub portions 51 secured to the shaft 33 and rotatable with and by said shaft and in slightly spaced relation to the driving pinion 37 so that there is a slight clearance between said rotating plates and the driving gear 11. The plates are of sufficient diameter and the wall 41 of the opening 40 is sufficiently inclined to permit the plates to not only overlap the toothed portion of the driving gear 11, but the plates project into and substantially thru the opening 40. The plates, therefore, laterally confine the oil at the meshing engagement and insures a substantially complete transfer of the oil from the gear to the pinion or to the plates, and the plates and pinion discharge the oil received from the gear upwardly thru the opening, whereupon it is distributed by the passageway as aforesaid.

To prevent splashing, a suitable cover construction 50 is provided which may be secured as at 51 to the reservoir 10. Said cover includes the openings 52 for the piston rod construction. As shown in Fig. 2, the channel or passageway 30 is completely filled with oil and the boss 31 guiding the piston rod is submerged. The groove 44 may and preferably is encircling in character relative to the reservoir, and immediately adjacent the bearings 13 or their equivalent, said groove includes partitions such as 44-a, which insure discharge of the oil or lubricant which discharges into the groove 44 adjacent the passageway 45 thru the same and to the bearing to the crank shaft drive.

60 The invention claimed is:

1. In combination a gear chamber constituting an oil reservoir, a gear therein adapted to run in oil in said chamber, a superposed gear meshing therewith, a cover for said chamber including an oil passageway for

gravity lubrication, and including an opening above the superposed gear for supplying the oil to the passageway from the latter, and a rotatable plate portion overlapping both gears at the meshing engagement for laterally confining the oil carried by the first-mentioned gear to the engageable portions of said gears. 70

2. In combination a gear chamber constituting an oil reservoir, a gear therein adapted to run in oil in said chamber, a superposed gear meshing therewith, a cover for said chamber including an oil passageway for gravity lubrication, and including an opening above the superposed gear for supplying the oil to the passageway from the latter, and a rotatable plate at each side of the superposed gear and extending toward the opening for forming an oil discharge channel and overlapping the first-mentioned gear at the meshing engagement for laterally confining the oil carried by the latter to the engageable portions of the gears. 75 80 85

3. In combination a gear chamber constituting an oil reservoir, a gear therein adapted to run in oil in said chamber, a superposed gear meshing therewith, a cover for said chamber including an oil passageway for gravity lubrication, and including an opening above the superposed gear for supplying the oil to the passageway from the latter, a wall projecting upwardly and defining said opening, and rotatable plates projecting into the opening and overlapping both gears at the meshing engagement thereof for laterally confining the oil carried by the first-mentioned gear to the engageable portions of said gears. 90 95 100

4. In combination a gear chamber constituting an oil reservoir, a gear therein adapted to run in oil in said chamber, a superposed gear meshing therewith, a cover for said chamber including an oil passageway for gravity lubrication, and including an opening above the superposed gear from supplying the oil to the passageway from the latter, a shaft supporting the superposed gear in position beneath said cover passageway and lubricated thereby, and plates carried by the shaft adjacent the superposed gear for rotation with and by the shaft in the rotation of the gear, said plates overlapping both gears and the meshing engagement for laterally confining the oil carried by the first-mentioned gear to the engageable portions of said gears. 105 110 115 120

5. A device as defined by claim 4 characterized by the plates projecting into the opening of said cover for forming an oil discharge channel therethru. 125

6. A pump including a pump cylinder, a piston therefor, piston rod reciprocating mechanism in spaced relation with the cylinder, a casing inclosing said mechanism including an apertured plate positioned above 130

the same and horizontally mounted and arranged to form a superposed lubricant reservoir, a gear pump within the casing and arranged to supply lubricant to the plate reservoir through an aperture thereof, and gravity feed passages supplying lubricant to the pump bearings and the mechanism.

5 7. A pump including a pump cylinder, a piston therefor, piston rod reciprocating mechanism in spaced relation with the cylinder, a casing inclosing said mechanism including an apertured plate positioned above the same and horizontally mounted and arranged to form a superposed lubricant reservoir, a gear pump within the casing and arranged to supply lubricant to the plate reservoir through an aperture thereof, gravity feed passages supplying lubricant to the pump bearings and the mechanism, and a 10 splash cover associated with said plate and casing and through which the piston rod extends.

15 8. In a power head the combination of a casing including a lubricant receiving chamber, a crank shaft rotatably mounted therein, a gear rotatable in lubricant in said casing and actuating said crank shaft, a piston rod operable by said crank shaft, a body portion including a lubricant supplying channel, a 20 power shaft in said body portion, a bearing positioned in said head for rotatably supporting said power shaft, said channel and said bearing having registering ports for supplying lubricant to said bearings, and a pinion on 25 said power shaft connected to said gear for rotating the same, said pinion receiving lubricant from said gear, and said body portion having an aperture therein for supplying lubricant discharged by centrifugal force 30 from said gear to said channel.

35 9. In a pump mechanism the combination of a power head, a pump cylinder and piston in superposed relation thereto, means spacing said cylinder from said head, and means 40 extending from the cylinder to the power head for actuating the piston in the former.

45 10. A device as defined by claim 9 characterized by said piston and power connecting means including a petticoat for discharging laterally such leakage as escapes from the 50 cylinder to prevent seepage to the power head.

In witness whereof, I have hereunto affixed my signature.

STUART DEAN.
